(57) **CLAIM**

The ornamental design for a machine cover, as shown and described.

DESCRIPTION

FIG. 1 is a front, right, and top perspective view of a machine cover, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a partial enlarged view of an area labeled 8 in FIG. 1 comprising a strap and buckle set.

The dash-dash broken lines illustrate portions of the machine cover which form no part of the claimed design. The long dash-short dash broken lines illustrate the boundaries and lead lines of the enlargement area and form no part of the claimed design.

1 Claim, 8 Drawing SheetsFIG. 1

FIG. 2

FIG. 3

FIG. 4

FIG. 5

FIG. 6

FIG. 7

FIG. 8
